HOWARD E. FRYE, OF LYMAN, NEBRASKA

COIN-CONTROLLED MECHANISM

Application filed March 19, 1931. Serial No. 523,663.

An object of this invention is to provide an improved coin-controlled mechanism.

A further object of the invention is to provide an improved manually-operable, coin-controlled mechanism.

A further object of the invention is to provide an improved manually-operable, coin-controlled, switch-closing mechanism.

A further object of the invention is to provide an improved switch-closing mechanism readily adjustable for manual operation with or without coin control.

A further object of the invention is to provide improved coin-measuring means in a coin-controlled mechanism.

A further object of the invention is to provide an improved coin-controlled mechanism wherein the act of closing a switch is accomplished through coin-measuring devices actuated by both the thickness and diameter of coins.

A further object of the invention is to provide improved means for eliminating magnetically-susceptible, spurious coins from the coin race of a coin-controlled, switch-closing mechanism.

A further object of the invention is to provide improved means for eliminating spurious coins of relatively soft material from a coin-controlled, switch-closing mechanism prior to completion of the switch-closing operation.

A further object of the invention is to provide improved means for obstructing the coin race of a coin-controlled mechanism when the operating elements of the mechanism are in other than normal coin-receiving position and relation.

A further object of the invention is to provide an improved coin-controlled, switch-closing mechanism susceptible of ready adaptation to electrically-operated machines and devices throughout a wide field, which mechanism is positive and efficient in operation, durable in use and relatively simple and inexpensive of manufacture and installation.

My invention consists in the construction, arrangement and combination of elements hereinafter set forth, pointed out in my

claims and illustrated by the accompanying drawings, in which—

Figure 1 is an elevation of one side of my improved mechanism as assembled for practical use, the elements being shown in normal or open switch position and one side of the mechanism housing being removed. Figure 2 is a horizontal section through the showing of Figure 1 on the indicated line 2—2 of the latter figure. Figure 3 is an elevation of the side of my improved mechanism opposite to that shown in Figure 1, the elements being positioned to correspond with the showing of Figure 1 and a portion of the mechanism housing being broken away to disclose otherwise concealed construction. Figure 4 is a fragmentary, detail section taken on the indicated line 4—4 of Figure 3, certain elements of the complete mechanism being omitted in favor of simplicity and clarity. Figure 5 is a detail end elevation of certain of the elements employed in the mechanism. Figure 6 is a vertical, detail section of an adjusting device employed in the mechanism.

In the construction of the improved mechanism as shown, the numeral 10 designates a base plate on and about which the elements of the mechanism are operatively arranged, said plate preferably being of metal, relatively thin, and of any suitable size and shape. The plate 10 should be positioned in a true vertical plane for successful operation of the devices carried thereby and may be supported in the desired position in any suitable manner. A face plate 11 is formed integrally with or permanently secured to one margin of the plate 10 and extends on both sides of said plate 10 in a vertical plane perpendicular to the plane of said base plate. As shown in Figure 1, a pin 12 is fixed to and projects perpendicularly from one side, hereinafter known as the switch side, of the plate 10 in the upper, forward portion of said plate, the face plate 11 being considered as defining the forward margin of the base plate 10, and a bracket 13 is mounted on and for oscillation in a vertical plane about said pin 12 adjacent the plate 10. Spring clips 14 rise in spaced relation from the upper surface of the

bracket 13 to retain and support a conventional mercury-type switch tube 15 in parallel relation with the upper surface of said bracket, said tube 15 being a common and well-known element comprising a sealed container housing a portion of mercury and the spaced terminals of a pair of electrical conductors 16 sealed through said container, said terminals and mercury being so arranged that when the tube is tilted with its conductor end lower than its plain end the mercury will envelop both of the spaced terminals and complete an electrical circuit through the conductors 16, which circuit is broken by flow of the mercury away from the terminals when the tube is tilted with its plain end lower than its conductor end, as illustrated in Figure 1. For convenience, the conductors 16 are led through binding posts 17 carried by the housing enclosing the mechanism and may be operatively connected with any suitable electrical device or apparatus and with a source of electrical energy in such manner as to permit control of such device or apparatus through the making or breaking of the circuit through the conductors 16 as determined by the relative position of the tube 15. Fixed to and independently relation with the bracket 13, an arm 18 is positioned to swing in spaced parallelism with the plate 10 as said bracket is rocked about its pivot 12, and a pin 19 is fixed at one end in the outer end of the arm 18 and extends therefrom in parallel relation with the pin 12 through an aperture 20 formed in the plate 10 to terminate in a forwardly-curved free end projecting some distance beyond said plate 10, engagement of the pin 19 with margins of the aperture 20 defining and limiting the range of oscillation of the bracket 13 and tube 15 between open and closed circuit positions of said tube. A lever 21 formed with a forked end 22 is pivoted at 23 to the switch side of the plate 10 with the prongs of its forked end 22 engaging opposite sides of the pin 19, said lever 21 extending downwardly from its pivot 23 to terminate in a forwardly-extending contact finger 24. A suitable device, such as a spring 25, connects the bracket 13 with the plate 10 in such a manner as to normally yieldingly retain said bracket at one or the other of its limits of oscillation. Reciprocable through a guide 26 on the switch side of the plate 10, a slide bar 27 is horizontally-disposed adjacent said plate in spaced relation beneath the switch assembly above described, the forward end of said bar 27 merging with a slide rod 28 forming an aligned extension of the bar 27, which rod 28 extends forwardly through a slide aperture in the plate 11 to terminate in a knob 29 spaced forwardly of the said plate 11. The slide assembly 27, 28 and 29 is thus positioned and supported for rectilinear reciprocation along the plate 10 and perpen-

dicular to the plate 11 by means of the guide 26 and slide aperture in said latter plate, and is normally retained at the forward limit of its range of operation by means of a retractile coil spring 30 connecting a lug on the bar 27 with a lug or ear of the plate 11. A cross-head 31 is formed at the junction of the bar 27 and rod 28 and is axially parallel with the plates 10 and 11, said cross-head 31 being traversed by a smooth axial bore wherein is received an adjustable rod 32. The rod 32 is loosely received in the bore of the cross-head 31 and projects at each end beyond the ends of said cross-head, the lowermost position of said rod being such as to position its upper end beneath and in position to clear the finger 24 of the lever 21, and its uppermost position being such as to position its upper end above and in engageable relation with said finger, pins 33 perpendicularly through said rod serving to limit the relative movement between said rod and the cross-head 31. As shown in Figure 6, an offset pocket 34 is provided on the cross-head 31 in communication with the bore thereof, said pocket housing a spring-pressed ball 35 operable to engage suitably positioned notches 36 in the rod 32 and yieldingly hold said rod in the desired relation with said cross-head. The relative position of the rod 32 determines whether oscillation of the switch tube 15 to close the circuit through the conductors 16 is to be accomplished with or without coin control, since with the rod 32 in its lowermost position, as illustrated by full lines in Figure 1, manual reciprocation of the slide assembly 27, 28, 29 simply moves the rod 32 as the assembly is moved without bringing said rod into engagement with any of the other elements of the mechanism and permitting operation of the coin-controlled mechanism hereinafter to be described; on the other hand, when the rod 32 is moved upwardly of the cross-head 31 to the position shown in dotted lines in Figure 1, rearward motion of the slide assembly operates to engage the upper end of the rod 32 against the finger 24 of the lever 21 and swing said lever about its pivot 23, which motion of the lever 21 acts through the fork 22, pin 19 and arm 18 to swing the bracket 13 about its pivot to circuit-closing position of the switch tube 15 carried thereby. Parallel with and above the slide bar 27 a slot 37 is formed in and through the plate 10, said slot extending from the rear margin of said plate across the major portion thereof toward the forward margin, and a slide block 38, H-shaped in cross section, is mounted in and arranged to slide freely along said slot, the parallel legs of the block 38 being thus positioned on opposite sides of the plate 10. On the switch side of the plate 10, the forward end of the block 38 is thickened to form a head 39 opposed to and adapted to be engaged at times by a lug 40

formed on and rising from the bar 27 and the rearward end of the block 38 on the switch side of the plate carries an upwardly and outwardly curved arm 41, whereto is attached 5 one end of a retractile coil spring 42 connecting said arm 41 with an ear or lug on the plate 11, it being the function of the spring 42 to normally position the block 38 with its head 39 in engagement with the lug 40, and to 10 return said block to normal position after displacement therefrom. To decrease the speed with which the block 38 is returned under the influence of the spring 42 and to minimize the shock resulting from sudden 15 stopping of said block, a piston 43 is adjustably fixed by means of its piston rod 44 to the upper outer end of the arm 41 in position to be slidingly received within the bore of a rearwardly-opening cylinder 45 carried 20 by the plate 10 in axially parallel relation with the slot 37, said piston and cylinder thus forming a conventional dash-pot whereby the speed of the block 38 is decelerated as it approaches its forward position through the 25 action of the spring 42. As should be readily apparent, inward pressure applied to the knob 29 acts to move the slide bar 27 rearwardly along the plate 10 against the pressure of the spring 30, the block 38 moving 30 simultaneously against the pressure of its spring 42 by virtue of the engagement of its head 39 with the lug 40 to withdraw the piston 43 axially of its cylinder 45; release 35 of the pressure on the knob 29 permitting the slide bar 27 to be promptly returned by its spring 30 while the block 38 follows more slowly as the piston and cylinder assembly 40 retards the action of the spring 42.

On the side of the plate 10 opposite to the 45 switch side, shown in Figure 3 and conveniently designated as the coin side of said plate, suitable plates 46 and spacing blocks 47 are assembled and arranged to form a downwardly and rearwardly directed coin race one 50 side of which is defined by the surface of the plate 10. The upper forward end of the coin race communicates with a vertically-disposed coin slot opening through the plate 11, said slot being indicated by dotted lines in Figure 55 3, said race being directed first downwardly along the plate 11, then rearwardly and downwardly across the plate 10 and finally downwardly and forwardly of the plate 10 to a coin discharge above the leg of the block 58 adjacent the coin side of said plate, so that 60 a coin inserted through the coin slot of the plate 11 drops and rolls through said race to a position of rest wherein it is marginally supported on and above said leg of the block 38 with its plane surfaces parallel with the plate 10, as indicated by dotted lines in Figure 3, a pin 48 being fixed to the plate 10 in position to be engaged by the forward margin of said coin and limit forward motion 65 of said coin along the block 38. As clearly

shown in Figure 4, the rearwardly-extending portion of the coin race is widened and provided with a short partition 49 dividing that portion of the race into two coin passages, the inner of which communicates with the coin drop wherethrough a coin must pass to be received on the block 38 and the outer of which terminates in a discharge opening not communicating with the switch-operating elements of the mechanism. On the outer wall of the plate 46 between the first coin drop and the partition 49 is mounted a permanent magnet 50, so arranged as to attract spurious coins of magnetically-susceptible material out of the coin passage adjacent the plate 10 and into the outer of the passages defined by the partition 49 whence said spurious coins are discharged clear of the operating elements of the mechanism, the strength of the magnet 50 being sufficient only to divert said spurious coins and not enough to arrest such coins in the race. Vertically-disposed in spaced, straddling relation with the rear portion of the block 38, a rock-shaft 51 is mounted for rotary oscillation between brackets 52 fixed to and projecting from the coin side of the plate 10, a radial arm 53 extending forwardly and outwardly from the upper end of said rock-shaft above the top plane of the block 38 to support a needle element 54 in spaced opposition with the coin position above said block. The needle element 54 is slidingly mounted in a bore of the arm 53 and is yieldingly positioned in maximum projection therewith by a leaf spring 55 fixed at one end to the arm 53 and bearing at its other end against the base of the element 54, a spring element 56 suitably engaging the rock-shaft 51 functioning to normally position the arm 53 in diverging relation with the plate 10. A curved finger 57 is fixed to the rock-shaft 51 and curves rearwardly and inwardly therefrom in overlying relation with a roller 58 carried by the rear end of the block 38, the inner, curved surface of the finger 57 normally contacting the periphery of the roller 58 by virtue of the action of the spring 56 and thus limiting the divergence of the arm 53 relative to the plate 10. When the block 38 is moved rearwardly along the slot 37, the roller 58 acts on the inner curved surface of the finger 57 to rotate the rock-shaft 51 and swing the arm 53 through a horizontal arc toward the plate 10, driving the point of the needle 54 sharply against the face of a coin positioned against said plate and above the block 38. Due to the shape of the finger 57, the movement of the arm 53 is rapid and brief, since as soon as the roller 58 has passed beneath said finger the spring 56 returns the arm 53 and finger 57 to normal position. Should a valid coin be in position at the lower end of the coin race, the point of the needle 54 will fail to penetrate said coin as the arm 53 is swung inwardly and said

needle will yield in the arm 53 against the pressure of the spring 55, the coin remaining in position ready for further operations when the arm 53 is swung away to normal position. 5 However, should a spurious coin of relatively soft material have passed through the race to the block 38, the needle point will penetrate the surface of such spurious coin as the arm 53 is flipped inwardly and take sufficient hold 10 of such coin as will enable it to draw the coin from the block 38 and free of the operating elements of the mechanism. Spurious coins extracted from the mechanism by the needle 54 fall from said needle on the outward movement of the latter to an inclined plane 59 whereby they are directed to an opening 60 in the plate 11 for return to the depositor. 15 On a pin 61 projecting perpendicularly from the coin side of the plate 10 above and 20 forwardly of the forward end of the block 38 is pivotally mounted one end of a U-shaped bracket 62 disposed with its base extending in substantially a horizontal plane rearwardly of the pin 61 and in spaced, parallel relation with the plate 10, the jaws of said bracket opening outwardly of and away from said plate, thus mounting said bracket for oscillation about its pivot 61 through a vertical arc 25 parallel with the plate 10. A disc 63 is mounted for rotation on and carried by the base of the bracket 62 between said base and the surface of the plate 10. On a pivot extending radially of the pin 61 between the jaws of the bracket 62 is mounted a rock-shaft 64, said rock-shaft being formed with a depending boss 65 on the lower end whereof a disc 66 is rotatably mounted in a substantially horizontal plane, and is further formed with an outwardly and rearwardly curved 30 arm 67 rising from said rock-shaft above and behind the free end of the pin 19, a spring 68 between and engaging the bracket 62 and arm 67 acting to normally retain said arm in maximum spaced relation with the plate 10. 35 A lug 69 projecting laterally from the coin race is positioned to engage behind the arm 67 and limit clockwise motion of the assembly above described about the pivot 61. When the operating elements of the mechanism are in coin-receiving position, as illustrated, the arm 67 is at its rearmost position as determined by the lug 69 and the forward end of the block 38 on the coin side of the plate 10 is entered behind the disc 66, thus 40 swinging the upper end of the arm 67 inwardly toward the plate 10 and behind the pin 19. As the block 38 is moved rearwardly, its forward end is withdrawn from behind the disc 66 and the spring 68 then acts to 45 swing the upper end of the arm 67 away from the plate 10 and into clearing relation with the pin 19, the limit of this motion being determined through contact of the disc 66 with the plate 10. As rearward motion of the 50 block 38 is continued, said block is withdrawn

from beneath the coin position and the coin therein is permitted to drop to a step 79 provided beneath said block and in front of the forward end of the retracted block, which step is fixed to the plate 10 and provided with an upstanding flange 80 spaced from said plate and arranged to steady the coin in upright position on said step. When the pressure applied to the knob 29 is released and the block 38 returns under the action of its spring 42, the forward end of said block engages the periphery of the coin and pushes the latter forward along the plate 10 into engagement with and behind the disc 66, which action swings said disc outwardly from the plate 10 against the pressure of the spring 68 and moves the upper end of the arm 67 inwardly into engaging position behind the pin 19. Further forward travel of the block 38 pushes the coin into marginal engagement with the disc 63, thus lifting said disc and swinging the bracket 62 through an upward arc about the pivot 61, consequently moving the upper end of the arm 67 forwardly against the pin 19 and thereby swinging the bracket 13 from open to circuit-closing position of the switch tube 15. In order to prevent introduction of a coin to the operating elements of the mechanism when the block 38 is retracted, a rod 70 is vertically journaled on the switch side of the plate 10 behind the cylinder 45 and is formed with a forwardly-extending upper end 71 bent to project at times through a hole 72 in the plate 10 and obstruct the coin race and a lower end portion 73 projecting through the plate 10 immediately above the block 38. A spring 74 engages the end 71 of the rod 70 to normally position said end 71 in obstructing relation with the coin race and a lug 75 is carried by the block 38 in position to engage the end portion 73 of the rod 70 as said block reaches its most forward position and rotate the rod 70 against the pressure of the spring 74 to swing the end 71 out of the coin race and into the position shown in Figure 2, any rearward motion of the block 38 disengaging the lug 75 from the rod portion 73 and permitting the spring 74 to act to again obstruct the coin race. 105

On the switch side of the plate 10 is pivotally mounted a lever 76 positioned with its inner end in engaging relation beneath one end of the bracket 13 and its outer end projecting beyond said plate 10 for connection with a pull-rod 77. The pull-rod 77 may be operatively connected with the device, apparatus or mechanism actuated through closing of the switch 15, so that, when said device, apparatus or mechanism has functioned to the desired extent a downward pull will be exerted on said rod 77, which pull, it is obvious, will rock the bracket 13 from closed to open circuit position of the switch tube 15, such connections, however, being no part of 110 115 120 125 130

the coin-controlled mechanism proper and varying with the type and nature of devices to which said mechanism is applied.

When the coin, under the influence of the 5 block 38, has actuated the bracket 62 and arm 67 to close the circuit through the switch tube 15, further forward motion of the said block 38 carries said coin forwardly along the plate 10 to the upper end of a coin drop through 10 which said coin descends under the influence of gravity to a coin box or similar receptacle (not shown) where the coins are collected until removed by an attendant, the bracket and arm assembly 62—67 returning to normal 15 position by the action of its unbalanced weight when the coin has ceased to engage the disc 63. The complete mechanism may be suitably enclosed in any desired manner, as by plates 78, and may be positioned and arranged for practical operation in the manner 20 best suited to the device or apparatus to be controlled therethrough.

In the practical operation of the mechanism, it is to be noted that all of the elements 25 of the mechanism return or are returned to normal coin-receiving position automatically and are actuated through manual operation of the push-rod 28 and the mechanical events subsequent to such operation, a simple adjustment of the rod 32 permitting closing of 30 the switch tube 15 directly and without employment of the coin-control, when desirable. A coin deposited through the coin slot of the plate 11 is tested in its progress through the 35 mechanism for magnetic susceptibility, for hardness, for thickness and for diameter, and the mechanism can readily be so adjusted that only coins successfully meeting these tests will close the circuit through the switch tube 40 15 and operate the device or apparatus controlled by the mechanism.

Since many changes and modifications in the specific form, construction and arrangement of the elements of the improved mechanism 45 may be had without departing from the spirit of the invention, I wish to be understood as being limited solely by the scope of the appended claims rather than by the illustrative showing and foregoing description.

50 I claim as my invention—

1. A coin-controlled, switch-closing mechanism comprising a switch element pivotally mounted for oscillation between open circuit and closed circuit positions to control an 55 associated apparatus, pivotally-mounted, switch-rocking means operable by the face and periphery of a proper coin to engage said switch element and move the latter from open circuit to closed circuit position, a coin race 60 arranged to position a coin adjacent said switch-rocking means, a fixed support for said coin adjacent said switch-rocking means and a manually-operable, spring-returnable 65 slide member adapted to engage said coin and move the latter through operative engage-

ment with said switch-rocking means during the return travel of said slide member; together with means operable by the associated apparatus to open said switch.

2. A coin-controlled, switch-closing mechanism comprising a switch element pivotally mounted for oscillation between open circuit and closed circuit positions to control an associated apparatus, an operating pin projecting from said switch mounting, pivotally-mounted, switch-rocking means operable through perpendicularly related, vertical arcs by the face and periphery of a proper coin to engage said operating pin and rock said switch element from open circuit to closed circuit position, a coin race arranged to position a coin adjacent said switch-rocking means, a fixed support for said coin adjacent said switch-rocking means and a manually-operable, spring-returnable slide member adapted to engage said coin and move the latter through operative engagement with said switch-rocking means during the return travel of said slide member; together with means operable by the associated apparatus to open said switch.

3. A coin-controlled, switch-closing mechanism comprising a switch element pivotally mounted for oscillation between open circuit and closed circuit positions to control an associated apparatus, pivotally-mounted, switch-rocking means operable by the face and periphery of a proper coin to engage said switch element and move the latter from open circuit to closed circuit position, a coin race arranged to position a coin adjacent said switch-rocking means, a fixed support for said coin adjacent said switch-rocking means, and a manually-operable, spring-returnable slide member adapted to engage a properly positioned coin and move the latter through operative engagement with said switch-rocking means during the return travel of said slide member, together with means operable by the associated apparatus to open said switch.

4. A coin-controlled, switch-closing mechanism comprising a switch element pivotally mounted for oscillation between open circuit and closed circuit positions to control an associated apparatus, pivotally-mounted, switch-rocking means operable through perpendicularly related, vertical arcs by the face and periphery of a proper coin to engage said switch element and move the latter from open circuit to closed circuit position, a coin race arranged to position a coin adjacent said switch-rocking means, a fixed support for said coin adjacent said switch-rocking means, a suitable, spring-returnable slide member adapted to engage a properly positioned coin and move the latter through operative engagement with said switch-rocking means during the return travel of said slide member, and a manually-operable, spring-returnable

slide bar positioned to engage said slide member for simultaneous, identical travel when said slide bar is moved, together with means operable by the associated apparatus to open said switch.

5. A coin-controlled, switch-closing mechanism comprising a switch element pivotally mounted for oscillation between open circuit and closed circuit positions to control an associated apparatus, pivotally-mounted, switch-rocking means operable by the face and periphery of a proper coin to engage said switch element and move the latter from open circuit to closed circuit position, a coin race arranged to position a coin adjacent said switch-rocking means, a fixed support for said coin adjacent said switch-rocking means a manually-operable, spring-returnable slide member adapted to engage a properly positioned coin and move the latter through operative engagement with said switch-rocking means during the return travel of said slide member, and means for decelerating the return speed of said slide member, said latter means comprising a fixed cylinder axially parallel with the path of travel of said slide member and a piston carried by said slide member axially of and arranged for axial reciprocation within said cylinder; together with means operable by the associated apparatus to open said switch.

6. A coin-controlled, switch-closing mechanism comprising a switch element pivotally mounted for oscillation between open circuit and closed circuit positions to control an associated apparatus, pivotally-mounted, switch-rocking means operable by the face and periphery of a proper coin to engage said switch element and move the latter from open circuit to closed circuit position, a manually-operable, spring-returnable slide member adjacent said switch-rocking means, a coin race arranged to deposit a coin on and above said slide member when the latter is in normal position, a fixed support adjacent said switch-rocking means arranged to receive and position said coin as said slide member is withdrawn from normal position; and penetrating means operable through motion of said slide member to briefly impinge against coins positioned by said race and by penetration therein withdraw spurious, soft-metal coins from the operating elements of the mechanism; together with means operable by the associated apparatus to open said switch.

7. In a coin-controlled, switch-closing mechanism having a switch element pivotally mounted for oscillation between open circuit and closed circuit positions to control an associated apparatus, an operating pin extending from said switch mounting whereby said switch element may be oscillated, a manually-operable, spring-returnable slide bar and coin-controlled elements operable by said slide bar to engage said pin and oscillate said

switch element, means carried by said slide bar and optionally adjustable to oscillate said switch element independently of said coin-controlled elements, said means comprising a lever of the first class pivotally mounted with one end operatively engaging said operating pin, a lug on the other end of said lever, and a rod carried by and axially adjustable between two positions relative to said slide bar, the range of adjustment of said rod being such as to permit said rod when in one position to pass in clearing relation with said lever as the slide bar is operated and when in its other position to engage against the lug of said lever during operation of said slide bar and move said lever to effect oscillation of said switch element; together with means operable by the associated apparatus to open said switch.

8. In a mechanism of the character described having a manually-operable, spring-returnable slide member and a coin race adapted to position a coin marginally on and above said slide member when the latter is in normal position, means operable to remove spurious soft-metal coins from said slide member during the operation thereof, said means comprising a rock shaft mounted for oscillation in spaced, straddling relation with the rearward end of said slide member and perpendicular to the path of travel of said member, a radial arm fixed to said rock shaft and extending forwardly and outwardly above said slide member, a spring-pressed needle in the outer end of said arm in opposition to the coin position above said slide member, spring means engaging said rock shaft to normally hold said needle in spaced relation with said coin position, a curved finger on said rock shaft extending therefrom oppositely to said arm in alignment with and spaced laterally from said slide member, and a roller on the rearward end of said slide member in position to engage said curved finger as said member is reciprocated, whereby said rock shaft is oscillated to swing said needle into brief impinging relation with coins positioned on said slide member through said race, said needle yielding against its spring upon contact with valid coins and penetrating spurious soft-metal coins for withdrawal of the latter during return motion of said arm and needle, and a coin support in fixed relation beneath and normally carried by said slide member wherein valid coins may be received during rearward travel of said slide member.

9. In a mechanism of the character described having a switch element mounted for oscillation to control an associated apparatus, an operating pin extending from the mounting of said element whereby the latter may be oscillated, a manually-operable, spring-returnable slide member and a coin race arranged to position a proper coin marginally

on and above said slide member, means operable by the face and periphery of said proper coin to engage said operating pin and oscillate said switch element, said means comprising a U-shaped bracket pivotally engaged at one end for actuation through a vertical arc, a vertically-disposed, coin-engaging disc carried by said bracket, a rock shaft mounted for oscillation between the arms of said bracket and radially of said bracket pivot, an arm rising from said rock shaft behind and normally in clearing relation with the outer end of said operating pin and a horizontally-disposed, coin-engaging disc carried by said rock shaft below said bracket; together with a coin step beneath said slide member and adapted to receive the coin supported by said member as the latter is operated, whereby said coin is positioned for engagement by said 20 slide member during return travel of the latter and for operative engagement under the influence of said slide member with the discs carried by said rock shaft and bracket, the face of said coin swinging said rock shaft 25 disc outwardly to move the arm of said rock shaft into engaging relation with the switch operating pin and the periphery of said coin moving said bracket disc, together with said bracket, rock shaft and arm, upwardly to 30 swing said arm forwardly against said operating pin and oscillate said switch element, and means operable by the associated apparatus to open said switch.

10. In a mechanism of the character described having a switch element mounted for oscillation to control an associated apparatus, a slideable, spring-returnable slide member, a coin race arranged to position a proper coin marginally on and above said slide member, 35 a coin support in fixed relation beneath and normally covered by said slide member, a switch-oscillating assembly operable by the face and periphery of a proper coin under the influence of said slide member and means for 40 testing the validity of coins prior to actuation of said switch-oscillating assembly thereby, manually-operable means for actuating said slide member, said means comprising a slide bar mounted for reciprocation beneath and 45 parallel with said slide member, a slide rod in alinement with and extending forwardly from said slide bar, a lug on and rising from the upper margin of said slide bar in position to engage against the forward end of said 50 slide member when said slide bar is moved rearwardly, a retractile coil spring operatively engaging said slide bar for the return of the latter to normal position, means for limiting the forward motion of said slide bar, 55 and automatic means for decelerating the return speed of said slide member, together with means operable by the associated apparatus to open said switch.

11. In a mechanism of the character described having a switch element mounted for

oscillation between open circuit and closed circuit positions to control an associated apparatus, a slideable, spring-returnable slide member, a switch-oscillating assembly adjacent said slide member, a coin race adapted to deposit a proper coin marginally on and above said slide member for positioning in operative relation with said switch-oscillating assembly during the rearward travel of said slide member and operative engagement with said assembly during return travel of said slide member, a coin support in fixed relation beneath and normally covered by said slide member, penetrating means operable by said slide member for the removal of spurious soft metal coins from said slide member prior to actuation of said switch-oscillating assembly, and manually-operable spring-returnable means whereby said slide member may be actuated, together with means operable by the associated apparatus to open said switch.

Signed at Denver, in the county of Denver and State of Colorado, this Twenty-second day of February, 1930.

HOWARD E. FRYE.
